UNITED STATES PATENT OFFICE.

ELLIS D. MILLER, OF BERKELEY, CALIFORNIA, ASSIGNOR TO NATIONAL PAPER PRODUCTS COMPANY, OF SAN FRANCISCO, CALIFORNIA, A CORPORATION OF CALIFORNIA.

LOCK FOR PAPER-CONTAINERS.

1,204,811.

Specification of Letters Patent. Patented Nov. 14, 1916.

Application filed March 7, 1916. Serial No. 82,647.

To all whom it may concern:

Be it known that I, ELLIS D. MILLER, a citizen of the United States, residing at Berkeley, in the county of Alameda and 5 State of California, have invented new and useful Improvements in Locks for Paper-Containers, of which the following is a specification.

This invention relates to an interleaved 10 paper container and dispenser and particularly to a lock for same.

The object of the present invention is to provide a container and dispenser for interleaved papers and particularly a simple, 15 cheaply manufactured easily operated keyless lock for same which can not be opened except by one familiar with or instructed in its operation.

Further objects will hereinafter appear. 20 The invention consists of the parts and the construction and combination of parts, as hereinafter more fully described and claimed, having reference to the accompanying drawings, in which—

25 Figure 1 is a perspective view of the interleaved paper container and dispenser. Fig. 2 is a central, vertical section through same, showing the application of the keyless lock. Fig. 3 is a cross section taken on line 3—3, 30 Fig. 2.

Referring to the drawings in detail, A indicates the container proper, consisting of a back section 2, two side plates 3 and a bottom section 4, which is provided with a 35 longitudinally disposed slot or opening 5 through which the interleaved paper sheets may be removed. Pivotally attached to the side plates 3, as at 6 is a cover section B, consisting of a front plate 7, two side plates 40 8 and a cover section 9. The pivotal mounting of the cover section B permits it to be turned from the closed position shown in Fig. 2 to the dotted line position indicated at 10, when it is desired to refill the container.

45 The main novelty of the present invention consists in the provision of a keyless lock which is provided for the purpose of securing the cover section with relation to the container A, when in the closed position. The construction of this lock will be as follows: Pivotally attached to the under side of the cover 9, as at 11, is a pair of latch arms 12. One end of each latch arm is

provided with a hook-shaped projection 14, 55 which in this instance is adapted to project through an opening 15, which is formed by cutting away a portion of a downwardly turned flange 16, formed on the back section 2 of the container. The hook-shaped ends 60 of the latch arm will normally tend to separate in the direction of the arrows to engage the opposite flange sections 16, thus securing the cover with relation to the container. This is accomplished by providing 65 a U-shaped spring 17. This spring is carried or suitably secured upon the pivot pin 11 and its outer ends are bent and extended to engage with the free ends 18 of the latch arms, as shown in Fig. 3. A stop 19 has 70 been provided for the purpose of limiting the movement of the latch arms about the pivotal point 11. Formed near the ends 18 of the latch arms is a pair of semi-circular depressions 20, which are positioned directly 75 in register with a circular-shaped opening 21, formed in the cover section 9. This opening is provided for the purpose of permitting the insertion of a pointed pencil or similar shaped device, which when inserted passes through the opening formed by the semi-circular depressions 20 to assume 80 a position intermediate of the ends 18 of the latch arms, where a downward movement of the pencil point will separate the 85 latch arms and cause same to assume the dotted line position, indicated at 22. This brings the hook-shaped ends 14 out of engagement with the flanges 16, thus permitting the cover section to be swung back 90 about the pivot 6 to assume the position shown at 10. The pencil or other device employed for the purpose of separating the latch arms, or in other words, releasing the lock mechanism may be removed the moment the cover section is released and partly 95 swung back about the pivot 6. The container may now be filled with the interleaved sheets and it will then only be necessary to swing the cover section back to 100 closed position. This brings the hook-shaped ends of the latch arms back into register with the flanges or shoulder 16, where they will latch and interlock to prevent opening of the cover section, except 105 in the manner described.

A lock constructed as here shown is simple, rigid and substantial; it is cheap to

manufacture and consumes a comparatively small space within the container; this being of considerable importance as it correspondingly increases the capacity of same.

5 The lock as before described is opened merely by the insertion of a pencil and can therefore be easily opened at any time without the use of a key. The lock mechanism being positioned directly under the cover 10 is entirely inclosed and hidden. Its mechanism can therefore not be seen or reasoned out by unauthorized persons who might otherwise have a tendency to tinker with or destroy the mechanism.

15 The materials and finish of the several parts of the device may otherwise be such as the judgment and experience of the manufacturer may dictate.

20 I wish it understood that various changes in form, proportions and minor details of construction may be resorted to within the scope of the appended claim, and that I do not wish to limit myself to the specific design and construction here shown.

25 Having thus described my invention, what I claim and desire to secure by Letters Patent is—

The combination with a container, a cover

section pivotally mounted thereon having a small circular pencil-receiving opening, 30 and a keeper on the container, of a lock carried by the cover section and adapted to be operated by the pointed end of a pencil and the like, said lock consisting of a pair of centrally pivoted arms carried 35 by the cover and recessed at their forward ends in alinement with the cover opening, latch members formed on the opposite ends of the arms for engaging with the keeper, spring means normally tending to hold the 40 forward ends together, and a stop pin disposed between the recessed end portions of the arms to hold the recesses in alinement with the cover opening and in slightly spaced relation, said stop pin further retaining the arms from swinging bodily 45 about their pivotal mounting and thereby hold the latch ends properly disposed for reception by the keeper.

In testimony whereof I have hereunto 50 set my hand in the presence of two subscribing witnesses.

ELLIS D. MILLER.
